J. G. B. CHAMBERS,
SHIPYARD AERIAL FALL CARRIER
APPLICATION FILED MAY 13, 1918.

1,294,770.

Patented Feb. 18, 1919.

UNITED STATES PATENT OFFICE.

JAMES G. B. CHAMBERS, OF SEATTLE, WASHINGTON.

SHIPYARD AERIAL FALL-CARRIER.

1,294,770.

Specification of Letters Patent. Patented Feb. 18, 1919.

Application filed May 13, 1918. Serial No. 234,075.

To all whom it may concern:

Be it known that I, JAMES G. B. CHAMBERS, a subject of the King of England, residing at Seattle, in the county of King and 5 State of Washington, have invented certain new and useful Improvements in Shipyard Aerial Fall-Carriers, of which the following is a specification.

This invention relates to aerial tramways 10 and, more particularly, to that class which is employed in shipyards for transporting structural material and has special references to the fall-line carriers.

The object of my invention is the perfecting 15 of devices of this character to render the same more efficient.

The invention consists in the novel construction, adaptation and combination of parts as will be hereinafter described and 20 claimed.

In the accompanying drawings, Figure 1 is a side elevational view of hoisting and conveying apparatus with the present invention applied thereto. Fig. 2 is a side elevation of 25 the fall carrier shown to a larger scale than in Fig. 1. Fig. 3 is an end view of the carrier taken from the right hand side of Fig. 2. Fig. 4 is a plan view of Fig. 2.

Referring to Fig. 1, the numeral 5 indicates a cable hereinafter designated as the "span cable" one end of which is secured to a post 6 and passing over a sheave 7 provided in a second post 8 and has its other end securely anchored. Said span cable serves as a 35 track for a load carriage A and also for the fall carriers, two of which B and B¹ are illustrated in the view. Said carriage, as shown is provided with a frame comprising spaced side plates, such as 9, in which are 40 journaled the axles of grooved wheels 10 which track on the span cable. 11 represents a load cable or fall having one end secured as at 11¹, to the post 6 thence passes over horizontally spaced sheaves 12 provided in the 45 carriage A and thence through a block 13 attached to the post 8 to a hoisting drum 14.

Between the sheaves 12 said fall extends 50 downwardly in the form of a bight which extends through a block 15 adapted to be detachably connected to a burden or load. 16 represents a drum about which is wound a number of times a transmission cable indicated by 17 which extends through a block or blocks on the post 8 and thence by a lead 17¹, 55 conventionally known as a "standing" transmission or lead to the carriage A to which it

is connected by a link 18. The cable also has a lead 17² known as the "running" transmission or lead extending between guide sheaves 19 on the carriage to a block 20 on the post 80 whence it returns by a second "standing" transmission lead 17³ to be connected by a link 18¹ to the carriage at its end opposite to that to which the standing lead 17¹ is connected thereto. The above described parts 65 are or may be constructed and arranged as in apparatus now in use, which operates as follows:

By driving the drum 16 in one rotary direction or the other, the transmission cable is 70 influenced to cause the carriage A to travel upon the span cable to a desired position. The drum 14 is then allowed or caused to turn to let out the fall 11 to lower the block 75 15 into position to receive a load. The drum 14 is then rotated to wind thereon the fall causing the load to be elevated into position for transporting by the carriage, through the agency of the aforesaid transmission cable.

According to the present invention, I provide 80 carriers for supporting the fall and transmission lines between the carriage and the respective posts, said carriers being operatively connected with such lines and the span cable so that the carriers will normally 85 travel upon the span cable in the direction of travel of the carriage but at slower speeds until the carriage approaches into proximity to one of the posts whereupon the adjacent carrier will be pushed by the carriage at the 90 speed of the latter.

Referring now particularly to Figs. 2, 3 and 4, a carrier comprises a main frame having two side members 22 and 22¹ rigidly connected in spaced relations by bolts 23 and 23¹ 95 passing through said frame members and interposed tubular distance pieces 24. Journaled in the upper portions of said frame members are the axles 25 of peripherally grooved supporting wheels 25¹ which travel 100 on the span cable 5.

Below this cable and having its axis in a transverse vertical plane between said wheels, is a peripherally grooved traction wheel 26 mounted on a pivotal pin 26¹ extending through vertical slots, such as 27, Fig. 2, provided in the frame members 22 and 22¹.

Rigidly secured to or formed integral with said traction wheel is a sheave 28 (Fig. 3) adapted to be rotated by frictional engagement at its under side with the associated standing transmission lead 17¹ or 17² 110

when the transmission cable is actuated to impart, through the agency of said traction wheel, motion to the carriage.

For the purpose of maintaining a standing transmission lead in frictional relation with a sheave 28, sheaves 29 and 29¹ are provided in the carrier frame to elevate the cable at the front and rear of the sheave 28 for forcing the latter upwardly and cause the wheel 26 to be tractively engaged against the span cable 5. The pin 26¹ of the wheel 26 and sheave 28 is journaled in substantially horizontal arms 30 of bell-crank levers fulcrumed to pins 31 supported in said frame members and in bracket attachments 32. The other arms 30¹ of said levers extend upwardly and are connected by pins 33 to the side elements 34 of a U shaped bar arranged horizontally and extending, as at 34¹, about the carrier frame at the rear, or end thereof which is adjacent to the carriage A. Below the wheel 26, each of the carriers is provided with a fall supporting sheave 35. A sheave 36, is provided for the running transmission lead 17² which travels in a direction opposite to that which the carriers travel. The sheave 36 is preferably mounted to rotate freely upon the pin 36¹ which carries the sheave 35.

An extension 37 is provided at the side of a carrier frame and has spaced elements 37¹ and 37² (Fig. 3) arranged to direct the lead 17² from an operating position as represented by full lines in Figs. 2 and 3 to a position indicated by dotted lines 17^a in Fig. 3 when the lead unduly sags as will sometimes occur.

Plates 38 are connected by bolts 39 and 39¹ to the carriage to serve as guides for the bar elements 34 and, to afford antifrictional supports for the latter, rollers 40 are mounted on the bolts 39¹ between frame members 22 and plates 38 below said bar elements. A roller 41 is also advantageously used on the bolt 23¹ above the sheave 35 to prevent any chafing of the fall when it rises from the sheave. Cushion pieces 42 (Fig. 1) of rubber or an equivalent material are provided on the ends of the carriage A so that in encountering the bars 34-34¹ of the respective carriers B or B¹ there will be produced but little shock.

In Fig. 1 a carrier is shown between the carriage and each of the posts, although additional carriers may be employed if desired. Ordinarily where two carriers are utilized each would occupy a position about midway between the carriage and the adjacent post until the carriage approaches within a short distance of one of the posts, as 6 for example, when the carriage would overtake a carrier as illustrated with respect to B¹. When the carriage A and carrier B¹ are in such relative positions the former is being pulled by the lead 17^a pushes the car-

rier through the medium of the bar 34-34¹ which is accordingly influenced to cause the bell-crank levers 30-30¹ to be actuated to lower the wheel 26 from the span cable 5 in opposition to a resistance exercised by the transmission lead 17³ against the sheave 28. When the wheel 26 is withdrawn from the span cable the carrier travels freely upon the same.

When a carrier, as B for example, is away from the carriage the standing transmission lead serves to retain the wheel 26 of a carrier in operative engagement with the span cable for propelling the carrier through the agency of the standing transmission lead.

Where a single carrier is employed between the carriage and a post the carrier should be provided with a wheel and sheave 26 and 28 of substantially the same diameters so that the speed of the carrier will be approximately one half that of the carriage and will occupy a position at about the mid distance between the carriage and the adjacent post. When more than one carrier, however, is employed in the space between the carriage and a post, the respective wheel and sheave 26 and 28 should be of diameters proportional to the speeds at which it is desired that the carriers should travel to occupy positions best suited to support the fall-line.

The invention will, it is thought, be understood from the foregoing description.

What I claim, is:—

1. In apparatus of the class described, the combination with a span cable, a load carriage mounted to travel thereon, a hoisting fall for said carriage, a transmission cable connected to the carriage, and means to actuate said transmission cable to effect the travel of the carriage, of a fall carrier having a pair of supporting wheels tracking on said span cable, a traction wheel subjacent to said span cable, means actuated by said transmission cable to operatively engage said traction wheel with the span cable to effect the travel of the carrier when the transmission cable is in motion, and devices connecting said means with the traction wheel for withdrawing the latter from said span cable to render the transmission cable inoperable to propel the carrier when said means is influenced by the carriage in the travel of the same.

2. In apparatus of the class described, the combination with a span cable, a load carriage mounted to travel thereon, a transmission cable having leads connected to said carriage, a drum for actuating said transmission cable to effect the travel of said carriage, a fall extending through the carriage, and means to operate said fall, of a fall carrier mounted to travel on said span cable, a vertically movable traction wheel provided on the carrier and urged upwardly

by said transmission cable for engaging said span cable, whereby the carrier is caused to travel in the same direction with but at a speed less than that of the carriage.

5 3. In apparatus of the class described, the combination with a span cable, a load carriage arranged to travel thereon, a power driven transmission cable to effect the travel of said carriage, a fall for the carriage, and

10 regulating means therefor, of a fall carrier provided with supporting wheels tracking on said span cable, levers provided on said carrier, a traction wheel, an axle therefor journaled in an arm of each of said levers,

15 a sheave mounted on said axle and adapted to rotate in unison with said traction wheel, guide sheaves for said transmission cable for directing the same into operative position with respect to said sheave whereby the traction wheel is rotated to propel said carrier, and means connected to said levers and influenced by being engaged by said carriage to render said traction wheel incapable of propelling the carrier.

20 4. In apparatus of the class described, the combination with a load carriage, a fall therefor, a span cable supporting the car-

riage, a power operated transmission cable for effecting the travel of the carriage, of a fall-carrier consisting of a frame, supporting wheels therefor mounted on said span cable, a traction wheel arranged for vertical movements in said frame, a sheave rotatable with said traction wheel, a pair of spaced sheaves supporting said span cable 30 at opposite sides of said sheave and serving through the medium of the latter to urge the traction wheel into engaging position with respect to said cable, and means engageable with said carriage and operatively 35 connected to said traction wheel whereby the latter is forced downwardly from its engagement with the span cable by depressing the transmission cable downwardly 40 through the instrumentality of the first named sheave between the aforesaid pair of spaced sheaves.

Signed at Seattle, Washington, this 2nd day of May 1918.

JAMES G. B. CHAMBERS.
